PORTABLE GRINDER FOR SHARPENING FLAT FACED BARBERS' CLIPPER CUTTERS OR THE LIKE

Frank R. Johnson, 3312 Tate St., Baltimore, Md.

Filed Sept. 13, 1960, Ser. No. 62,129

Term of patent 14 years

(Cl. D37—1)

FIGURE 1 is a perspective view of a portable grinder for sharpening flat faced barbers' clipper cutters or the like showing my new design.

I claim:

The ornamental design for a portable grinder for sharpening flat faced barbers' clipper cutter or the like, as shown.
